UNITED STATES PATENT OFFICE.

MARTIN A. THIEL, OF MILWAUKEE, WISCONSIN,

SINGLE-PIECE SPRING-VALVE.

No. 856,314.

Specification of Letters Patent.

Patented June 11, 1907.

Application filed May 31, 1904. Serial No. 210,612.

To all whom it may concern:

Be it known that I, MARTIN A. THIEL, a citizen of the United States of America, residing at Milwaukee, in the county of Milwaukee and State of Wisconsin, have invented certain new and useful Improvements in Single-Piece Spring-Valves, of which the following is a specification.

This invention relates to spring valves and has for an object the production of a flap valve of simple construction which will be effective and accurate in operation.

A further object is the production of a valve of this class which will move rapidly and act positively and still answer to the slightest variations of the actuating pressure.

A difficulty encountered in valves of this class has been the tendency of the valve spring to break, due to an unequal distribution of the distorting strains throughout its length. In overcoming this difficulty my object has been to construct a valve that will be durable and at the same time cheap to manufacture.

These and other objects I attain in a valve embodying the features herein described and illustrated.

In the single sheet of drawings accompanying this application and forming a part thereof, Figure 1 is a plan view of a valve embodying my invention. Fig. 2 is a section along the line AA of Fig. 1. Fig. 3 is a section along the line BB of Fig. 2. Fig. 4 is a plan view at a reduced scale of the valve with the spring portion developed or uncoiled.

The spring valve consists of an integrally formed valve portion 5, spring portion 6 and a mounting portion 7, and is of such simple construction that it may be stamped or cut out of a metal blank of uniform thickness. A centrally located and longitudinally extending slot 8 is cut in the spring portion 6 between the valve portion 5 and the mounting portion 7 and this slot is widest at a point adjacent to the portion 7 and tapers toward its narrowest part, which is adjacent to the valve portion 5. By this arrangement the effective area of the spring is gradually reduced from the part of largest section, which is adjacent to the valve portion, to the part of smallest section, which is adjacent to the mounting portion. This is done for the purpose of proportioning the sectional area of the spring in accordance with the variations in bending moment encountered throughout its length, so that each portion of the spring

will deflect or give an equal amount. In otherwords, the spring is so constructed that the portion encountering the smallest bending stress is made weakest and the portion encountering the greatest bending stress is made the strongest, and the sectional area is proportioned throughout the length of the spring in accordance with the encountered stresses so that the strains cross bending are substantially equal along the length of the spring. After the spring is stamped or cut from the blank the valve and mounting portions may be given any desired contour and the spring portion coiled. The spring portion is preferably made long enough to permit of several coils and the mounting portion is preferably provided with laterally extending projections 9 which are effective in insuring the desired amount of clearance between the outer edges of the spring portion and adjacent mounting members. By gradually reducing the effective area of the spring portion the bending or distorting strain is equally distributed throughout the length of the spring and an equal distortion of the separate coils is obtained and they will therefore always act independently of each other and not contact or bind.

In Figs. 1 and 2 the spring valve is shown mounted on an arbor 10 and adapted to control the flow of fluid through ports 11 of a valve seat 12. The valve herein illustrated is adapted to be opened by fluid pressure exerted on the under side of the valve portion 5, and by properly proportioning the width of the slot 8 the strength of the spring portion relative to the strength of the valve portion 5 may be made such that the spring portion will distort sufficiently to open the valve any desired amount before the valve portion 5 is subjected to an appreciable stress. Moreover, by tapering the slot so as to decrease the cross sectional area of the spring in proportion to the bending or distorting strains encountered throughout its length each coil will yield equal amounts and therefore a flexible spring and an active and positive valve is obtained. In spring valves in which the strength of the spring portion is not made considerably less than that of the valve portion it has been noted that the valves break adjacent to the point of merger of the valve and spring portions. This fracture is due to excessive strains encountered at that point and the tendency to fracture is overcome in a valve constructed in accordance with my in-

vention by relieving the valve portion of bending strains and proportioning the effective area of the spring to the distorting strains encountered along its length. The spring portion of the valve may be of any desired width and may be provided with two or more weakening slots; the mounting and valve portions may be of any desired shape and contour and many and various changes may be made in the combination and still fall within the limits and scope of my invention.

What I claim as new and useful is:

1. In a valve, a plane valve portion and a coil spring support therefor having a central longitudinal part cut away in increasing amount at increasing distance from the valve portion.

2. A spring valve comprising an integrally formed valve portion, a spring portion provided with a longitudinally extending and tapered slot and a mounting portion.

3. A spring valve comprising an integrally formed valve portion, spring portion and mounting portion of equal thicknesses, the spring portion being cut away longitudinally and increasingly from the valve portion to compensate the variations in the distorting strains.

4. A spring valve comprising an integrally formed valve portion, spring portion and mounting portion, the spring portion being

cut away longitudinally and increasingly from the valve portion to compensate the variations in the distorting strains.

5. A blank for a single piece valve comprising a substantially rectilinear strip of sheet metal, a valve portion at one end, a mounting portion at the other end and an intermediate spring portion which is cut away longitudinally and increasingly from the valve portion toward the mounting portion.

6. A blank for a single piece valve comprising a substantially rectilinear strip of metal, a valve portion at one end, a mounting portion at the other end and an intermediate spring portion which is cut away centrally, longitudinally and increasingly from the valve portion toward the mounting portion.

7. A blank for a single piece valve comprising a substantially rectilinear strip of sheet metal, a valve portion at one end, a mounting portion at the other end and an intermediate spring portion which is provided with a longitudinally-extending and tapered slot.

In testimony whereof I affix my signature in presence of two witnesses.

MARTIN A. THIEL.
